UNITED STATES PATENT OFFICE.

EDGAR M. SMITH, OF NEW YORK, N. Y., ASSIGNOR TO WILLIAM R. DAVIS, TRUSTEE, OF NEW YORK, N. Y.

RAIL-JOINT.

No. 922,533.

Specification of Letters Patent.

Patented May 25, 1909.

Application filed May 14, 1906. Serial No. 316,729.

To all whom it may concern:

Be it known that I, EDGAR M. SMITH, a citizen of the United States, residing at New York city, county of New York, State of New York, have invented a certain new and useful Improvement in Rail-Joints, and declare the following to be a full, clear, and exact description of the same, such as will enable others skilled in the art to which it pertains to make and use the same, reference being had to the accompanying drawings, which form a part of this specification.

My invention relates in general to rail joints, and more particularly to a joint for connecting rails of different heights.

In laying tracks it sometimes occurs that the adjoining rails are of different cross section and consequently it is impossible to use the ordinary joint plates. In such event it is desirable that joint plates should be employed which will securely unite and at the same time so support the adjoining ends of the rails that their tread surfaces will accurately align.

The primary object of my invention is to provide a rail joint for connecting the ends of rails of different heights which will support the bases of the rails at different levels so that the tread surfaces will be in the same horizontal plane, and which will also resist the downward strain at the joint incident to the passage of trains.

A further object of my invention is to provide a rail joint plate for uniting the ends of adjoining rails of different heights, which will be simple in construction, inexpensive in manufacture, and will possess great structural strength.

The embodiment of my invention herein disclosed may be generally described as consisting of a pair of joint plates each plate comprising an upper chord or fish plate of two different heights so as to fit snugly between the heads and bases of the united rails and conforming to the shape of the base flanges of the rails, a lower chord depending from the upper chord and extending below the bases of the rails, a flange underlying and supporting the base of the smaller rail, and a shoulder for supporting the base of the larger rail at a lower level than the base of the smaller rail.

My invention will be more fully described hereinafter with reference to the accompanying drawing in which the same is illus-

trated as embodied in a convenient and practical form, and in which,

Figure 1 is a perspective view; Fig. 2 an elevational view of the opposite side of the joint plate from that shown in Fig. 1; Fig. 3 a sectional view on line 3-3 Fig. 2; and Fig. 4 a sectional view on line 4-4 Fig. 2.

The same reference characters are used to designate the same parts in the several figures of the drawing.

Reference characters A' and B' indicate the upper chord or fish plate which is of two different heights to fit snugly between the heads and base flanges of adjoining rails of different heights. The portion A' extends slightly higher than the portion B' as it engages the smaller rail, the under surface of the head of which must be supported at a slightly higher level than the under surface of the head of the larger rail in order that the tread surfaces of the rails may align. The portion A' of the joint plate is provided with a base flange D' adapted to extend beneath the base of the smaller rail and support the same at a higher level than the base of the larger rail. At the inner end of the flange D' is formed a shoulder d' upon which is adapted to rest the base of the larger rail such shoulder being in a lower plane than the flange D' so that the base of the larger rail will be supported such a distance below the base of the smaller rail that the treads of the two rails will align horizontally.

In order that the downward strain to which the joint plates are subjected may be resisted, a lower chord C' is provided which depends below the base flange of the rails. The lower chord is strengthened by means of webs c' c' which extend downwardly in inclined directions from the feet a' b' of the joint plate. The lower chord C is further strengthened by the base flange D' of the portion A' of the plate and serves to support the shoulder d'. The joint plate is made integrally so that the lower chord, base flange D', and shoulder d' serve to mutually reinforce each other. The two plates employed to form a joint are the reverse in construction of each other in order that the portions of the plates adapted to support the lower rail may be opposite each other and the portions of the plates for engaging the large rail may also lie on the opposite sides of the end of such rail.

By reference to Figs. 3 and 4, it will be seen that the smaller rail E' is secured between the corresponding portions A' A^2 of the joint plates and that its base rests upon the base flanges D' D^2 of the respective plates. In Fig. 4, E^2 indicates the larger rail engaged by the corresponding portions B' B^2 of the joint plates. The base e^2 of the larger rail rests upon the corresponding shoulders d' d^2 and is thereby supported at a lower level than the base e' of the smaller rail.

From the foregoing description it will be observed that I have invented an improved rail joint for securely uniting the ends of rails of different heights and which is also adapted to withstand the downward strain to which a rail joint is subjected.

Having now fully described my invention, what I claim as new and desire to secure by Letters Patent is:

1. A joint plate for uniting the ends of rails of different heights, comprising an upper chord of two different heights to fit between the heads and base flanges of the rails, a lower chord adapted to project downwardly below the base flanges of the rails, said upper chord having flange sections projecting outwardly beyond said lower chord at the end thereof to form feet and having also an inwardly-projecting flange adapted to underlie and support the base of one of said rails.

2. A joint plate for uniting the ends of rails of different heights, comprising an upper chord of two different heights adapted to fit between the heads and base flanges of the rails, said chord having an outwardly-projecting flange, a portion of said flange being projected downwardly so as to form a lower chord, the remainder of the flange forming feet adjacent to the upper end of said downwardly-projecting chord, and an inwardly-extending flange on said upper chord arranged to underlie and support the base of one of said rails.

3. A joint plate for uniting the ends of rails of different heights, comprising an upper chord of two different heights adapted to fit between the heads and base flanges of the rails, said chord having an outwardly-projecting flange a portion of said flange being projected downwardly so as to form a lower chord, the remainder of the flange forming feet adjacent to the upper end of said downwardly-projecting chord, an inwardly-extending flange on said upper chord arranged to underlie and support the base of the smaller rail, and a shoulder at one end of said latter flange for underlying and supporting the base of the larger rail.

4. A step-joint for railway-rails comprising a pair of splice-bars adapted to be secured to opposite sides of the adjoining ends of rails of different cross-sectional area, each

of said splice-bars being formed of a substantially vertical rail-supporting web enlarged or stepped up vertically for substantially half its length to support the head of the smaller rail, and with a downward and outward inclined flange along the lower edge of said vertical web, an inward-extending base-support adapted to extend under one of the rails, said base-support terminating substantially midway between the ends of the bars, and a second inward-extending base support adapted to extend under the other rail.

5. A step-joint for railway-rails comprising a pair of splice-bars adapted to be secured to opposite sides of the adjoining ends of rails of different cross-sectional area, each of said splice-bars formed with a substantially vertical rail-supporting web enlarged or stepped up vertically for substantially half the length, to support the head of the smaller rail, and along the lower edge of said web with a downward and outward inclined flange adapted to extend over the base of the rails, one of said splice-bars being formed with an inward-extending base-support adapted to lie under the end of one of the rails, said base-support terminating substantially midway the ends of the splice-bar, and a second inward-extending base support adapted to underlie the other of said rails.

6. A step-joint for railway rails comprising a pair of splice-bars adapted to be secured to opposite sides of the adjoining ends of rails of different cross-sectional area, each of said splice-bars being formed of a substantially vertical rail-supporting web enlarged or stepped up vertically for substantially half its length to support the head of the smaller rail and with a downward and outward inclined flange along the lower edge of said vertical web, and a base-support extending inward under the base of the rail below the enlarged part of the vertical web and substantially equal in length to the enlarged part of the web, whereby said base-support extends under and carries the smaller rail and being of sufficient thickness to bring the upper surface of the said rail flush with the upper surface of the larger rail, and a second inward-extending base support adapted to underlie the other of said rails.

7. A connecting plate for railway offset joints, comprising a main upright portion having a vertical offset therein, outwardly and upwardly beveled bearings at the upper edge of said main portion, outwardly and downwardly inclined flanges at the bottom of said main portion, a lower vertical portion depending from said flanges beneath the offset in the main vertical portion, an inwardly extending base support connected to said main portion and extending from said lower vertical portion to one end of the main portion, and a second base support

extending inwardly from said lower vertical portion.

8. A joint plate for uniting the ends of rails of different heights, comprising an upper chord of two different heights to fit between the heads and base flanges of the rails, said upper chord having an outwardly projecting flange of sufficient width to extend beyond the base of the rails so as to

10 form feet and an inwardly-projecting flange lying in the plane of the feet and adapted to

underlie the base of one of the rails, and a downwardly-projecting chord extending beneath the plane of the feet between the ends of said plate.

15

In testimony whereof, I sign this specification in the presence of two witnesses.

EDGAR M. SMITH.
